UNITED STATES PATENT OFFICE.

JOHN L. FRUIN, OF CHICAGO, ILLINOIS; ROBERT E. FRUIN EXECUTOR OF THE SAID JOHN L. FRUIN, DECEASED.

PLUMBING SYSTEM.

Application filed June 19, 1922. Serial No. 569,452.

To all whom it may concern:

Be it known that I, JOHN L. FRUIN, a citizen of the United States, residing in Chicago, in the county of Cook and State of Illinois, have invented certain new and useful Improvements in Plumbing Systems, of which the following is a specification.

This invention relates to plumbing systems of the type designed for use in multiple 10 story buildings; and wherein the soil and vent stacks and vent and waste branches connected thereto are all located within a vertical wall of the building, extending from the lower floor to the roof, and are designed 15 and adapted to serve a plurality of bathroom and kitchen fixtures.

Plumbing systems of this general type are in very extensive use, and have heretofore involved a quite complicated organization 20 and arrangement of pipes and fittings for the accommodation of the various fixtures served, thereby involving considerable expense of material and labor in their installation. One object of the present invention is to provide a plumbing system of 25 this type possessing greater simplicity of structure and fewer parts than similar systems now in vogue.

A further specific object of the invention is 30 to provide a plumbing system of the type referred to adapted to serve both bathroom and kitchen fixtures which shall do away with what are known in the art as "jumpovers;" that is, curved or bent portions in 35 either the main vent pipe or a waste pipe which are situated in the same vertical plane and cross each other, thus making it necessary to bow or bend one of the pipes outwardly past the other.

40 A plumbing system assembled and erected in accordance with my present invention is illustrated in the accompanying drawing, in which—

45 Fig. 1 is a vertical section through the roof and several floors of a multiple story building showing my improved plumbing system in elevation therein; and

Fig. 2 is an enlarged horizontal section,

looking downwardly, on the line 2—2 of Fig. 1.

Referring to the drawing, 1, 2 and 3 indicate the first, second and third floors, respectively, and R the roof of a three-story building, and 4 and 5 designate the opposite sides of a hollow vertical wall structure 50 which may be assumed to extend the full height of the three stories, within which my improved plumbing system is located. This latter includes the usual main waste and vent stack 6 extending through the roof 60 R, and in which is included at each of the three floors a sanitary waste and vent fixture 7 herein shown as embodying the structure of the sanitary T forming the subject matter of Letters Patent No. 849,383 granted 65 to me April 9, 1907; but the specific structure of the said fixture is not material to the present invention.

Spaced at some distance from the main waste and vent stack 6 is the revent stack 70 comprising mainly the vertical pipe sections 8 which extend through the second and third floors.

Lying between the main waste and vent stack and the revent stack at each of the 75 several floors, and communicating with both of said stacks, is a combined waste and vent branch assembly through which the lavatory L and bathtub B are discharged and vented 80 at all three floors, the closet C is vented at the first and second floors, and the kitchen sink S is vented at all three floors. An important element of this combined waste and vent branch assembly consists of an 85 integral or one-piece fitting, the same including a pair of vertical limbs 9 and 10, and horizontal upper and lower limbs 11 and 12, respectively, communicating with the vertical limbs 9 and 10. At the top floor 3, one end of the upper horizontal limb 11 90 is connected directly into the main waste and vent stack 6 by a horizontal pipe section 13; while on the second and first floors the same end of the upper horizontal limb 11 is connected into the vent branch of the 95 soil pipe fitting 7 by connected horizontal

and vertical branch pipe sections 13' and 14.

On the opposite side of the vertical limbs 9 and 10 the upper horizontal limb 11 at all three floors communicates with the revent stack 8; at the top floor by an integral down-turned branch 11^a, and at the intermediate floor by a T head 11^b, and at the bottom floor by an up-turned branch 11^c.

One end (the right as herein shown) of the lower limb 12 of the fitting is connected by a horizontal pipe section 15 directly into the auxiliary waste inlet 16 of the soil pipe fitting 7; while the left end 17 of the lower limb 12 receives the drain pipe 18 from the 15 bathtub B.

Substantially mid-height of the vertical limb 9 is a short lateral branch 19 which receives the drain pipe 20 from the lavatory L. The discharge pipe 21 from the closet 20 leads into the main waste branch 22 of the soil pipe fitting 7 as usual.

My improved plumbing system employs for the discharge of the kitchen fixtures an auxiliary waste and vent stack leading into 25 a catch basin; such auxiliary waste and vent stack for kitchen fixtures being required by municipal sanitary regulations in some municipalities.

This auxiliary waste and vent stack is, in 30 accordance with my present invention, located in the same vertical plane with the main waste and vent stack 6 and the revent stack 8, and preferably on the opposite side of the latter from the main waste and vent 35 stack. As herein shown this auxiliary waste and vent stack comprises mainly the straight vertical pipe section 23 extending through the three floors and connected just above the latter by Y fittings 24 herein 40 shown as like those disclosed in Letters Patent to Fruin and Walker No. 675,090, granted May 28, 1901; but the specific structure of said fitting is not material to the present 45 invention. At the top floor the fitting 24 may be replaced by a simple straight fitting 24' having a lateral discharge branch 25'. The fittings 24 are formed with lateral discharge branches 25 which, together with the branch 25' connect with the drain pipes 26 50 leading from the sinks S.

To properly vent the traps of the sink discharge pipes, the upper limb 11 of the top floor fitting is formed with an integral downwardly-turned branch 27 connected 55 into the upper end of the fitting 24'; the T head 11^b of the fitting on the intermediate floor is formed with a downwardly-turned branch 27^a entering the vent branch of the fitting 24; and the upper limb 11 of the lower floor fitting has an integral downwardly extending branch 27^b also connecting with the vent branch of the lowermost fitting 24. By means of the branches 27, 27^a and 27^b of the several combined waste and vent fit-

tings the upper, intermediate and lower 65 auxiliary waste pipe fittings 24' and 24 are vented to and through the revent stack and its top end connections to the main waste and vent stack.

The manner in which the several fixtures 70 are discharged and their seals or traps vented to avoid danger of siphonage will be readily apparent to plumbers and others skilled in the art from the foregoing description of the structure and organization. It will be observed, however, that the vertical revent stack, which lies in the same vertical plane with the main and auxiliary waste and vent stacks, is so situated relatively to the drain 75 and vent pipes leading into the said stacks 80 that "jumpovers" are avoided and only straight sections of pipe and fittings are required for the make-up of said revent stack.

Heretofore in erecting systems of this 85 general type it has been customary to build up the intra-wall portions of the waste and vent branches of the lavatory and bathtub, and in some cases of the kitchen sink also, from a plurality of connected pipes and fittings, as typically illustrated in my former 90 Patent No. 740,412, dated October 6, 1903. In my present invention I greatly reduce the number of individual pipe sections and fittings required by combining these several 95 pipe sections and fittings of the old art in a single integral fitting which includes a part that merges into and forms a portion of the revent stack and likewise branches that connect up with the discharge fittings of an auxiliary waste and vent stack. Bearing in 100 mind that the greater the number of joints in a plumbing system, the greater is the danger of leakage, it is manifest that my present system by materially reducing the 105 number of joints, to that extent possesses more sanitary character and a higher degree of safety.

I claim:

1. In a plumbing system of the character described, the combination of a main vertical soil stack, an auxiliary vertical soil stack, a straight vertical revent stack disposed between said main and auxiliary soil stacks and nearer to the latter than to the former, a combined waste and vent pipe assembly 110 for fixtures lying between and connected into said main soil and revent stacks, and a vent connection between said auxiliary soil stack and said revent stack.

2. In a plumbing system of the character described, the combination of a main vertical soil stack, an auxiliary vertical soil stack, a straight vertical revent stack disposed between and in the vertical plane of 115 said main and auxiliary soil stacks and closely adjacent to the latter, a combined waste and vent pipe assembly for fixtures lying between and in the plane of said main 120 soil stack and said revent stack.

soil and revent stacks and connected into both of said stacks, and a vent connection between said auxiliary soil stack and said revent stack.

5. 3. In a plumbing system of the character described, the combination of a main vertical soil stack, an auxiliary vertical soil stack, a straight vertical revent stack disposed between and in the vertical plane of

said main and auxiliary soil stacks, a combined waste and vent pipe assembly for fixtures lying between and in the vertical plane of said main soil and revent stacks, and a pipe formed as an integral extension of a member of said assembly connected into 15 said auxiliary soil stack and venting the latter to said revent stack.

JOHN L. FRUIN.
